UNITED STATES PATENT OFFICE.

GARFIELD DAVIS, OF SPOKANE, WASHINGTON.

AUXILIARY LIFT FOR ROAD-WORKING APPARATUS.

Application filed September 14, 1921. Serial No. 500,515.

To all whom it may concern:

Be it known that I, GARFIELD DAVIS, a citizen of the United States of America, residing at Spokane, Spokane County, State 5 of Washington, have invented new and useful Improvements in Auxiliary Lifts for Road-Working Apparatus, of which the following is a specification.

This invention pertains to road working 10 apparatus and particularly to road graders, planers, scrapers, scarifiers and the like where the road contact tool or blade requires adjustment from time to time and particularly where the adjustment is required to be done by manual effort.

In order to meet the modern demand for 20 road building and upkeep, apparatus of the character mentioned has become large, heavy and to a great extent unwieldy, especially as pertains to the adjustment of the road contact tool or blade, and the object of this invention is to provide an auxiliary lift to aid in the manual adjustment and manipulation of the road contact tool 25 or blade. The invention consists in the application, for the purposes mentioned, of well known mechanical principles, whereby the weight required to be lifted by manual effort is greatly lightened and the process 30 of adjustment is facilitated and the apparatus made wieldy and practical.

The invention will be hereinafter particularly described, pointed out in the claims and illustrated in the accompanying drawings, 35 wherein application of the invention is made to a road grader.

Figure 1 is a side elevation of a road grader with the invention applied thereto.

Figure 2 is a partial rear end plan view 40 of the grader, showing the means for manual operation of the road contact tool or blade, the plan on which the figure is taken being indicated by line 2 in Fig. 1.

Figure 3 is a sectional view taken on the 45 line 3—3 of Figure 1.

Figure 4 is a side elevation of an enlarged view of the invention shown as applied to the grader, necessary connecting parts of the grader only being shown.

Figure 5 is a sectional view taken on the 50 line 5—5 of Figure 4, and

Figure 6 is a sectional view taken on the 55 line 6—6 of Figure 4.

In the following detail description in 55 which like nominals refer to like parts throughout the several views, sufficient of

the grader construction will be described to show the application of the invention. Front and rear trucks 10 and 11 respectively carry the frame of the grader including the 60 arched supports 12. Lift shafts 13 are rotatably mounted in bearings 14 and 15.

The ends of the lift shafts 13 adjacent the bearings 15 have rigidly secured thereto gears 16, which mesh with worm gears 17 65 rigidly secured to shafts 18 rotatably mounted in standards 19, one on each side of a platform 20, adjacent the ends of the arched supports 12. Rigidly mounted on the shafts 18 inside of the standards 19 70 are wheels 21 adapted to be manually turned for the operation of the lift shafts 13. The ends of the lift shafts 13 adjacent the bearings 14 are bent to right angles thereby forming cranks 22, which are 75 pivotally attached to downwardly extending lift rods 23, the lower ends of which are secured to a cross bar 24, carrying a steel circle 25, from which is suspended as by means of arms 26 and supports 27, the 80 scraper bar 28. A great weight is carried by the lift rods 23 and in the required changes in the elevation of the scraper bar 28 in the practical use of the grader the operator, by means of the connections between 85 the wheel 21 and the lift rods 23, must raise and lower the bar 28. To lighten the work of the operator in effecting these adjustments, the mechanism hereafter described has been provided.

Loosely mounted on the lift shafts 13 are sleeves 29, Figures 4 and 5. On the outer surface of the sleeves 29 are mounted coil springs 30. On the lift shafts 13 near the outer ends of the sleeves 29 are secured as 90 by the screws 31, countersunk into the shafts 13, lugs 32, to which the outer ends of the coil springs 30 are secured. Loosely mounted on the lift shafts 13 near the inner ends of the sleeves are ratchet wheels 33. Secured to the curved supports 12 adjacent the ratchet wheels 33 are arms 34 carrying gravity pawls 35 adapted for engagement with the ratchet wheels 33. Through the ratchet wheels 33 extend openings 36 and in 100 these openings 36 the inner ends of the coil springs 30 are secured. The longitudinal position of the ratchet wheels 33 on the lift shafts 13 is maintained by means of collars 37 engaging the shafts 13 and held in position by set screws 38. The coil springs attached to the ratchet wheels 33 as stated aid

in this positioning. The tension of the springs 30 is adjusted by means of the ratchet wheel 33 and pawl 35.

- In the adjustment of the scraper bar 28 from one extreme position to another, the lift shaft 13 is rotated only 180 degrees. When the scraper bar 28 is released from an elevated position to be lowered for use the cranks 22 turn from the position shown in Figure 4 outwardly and downwardly and by the anchoring of the coil springs 30 as shown, this movement serves to put a tension on the springs 30 which aids in the manual operation of lifting the scraper bar in proportion to the size and tension of the springs 30 and these springs may be of a sufficient strength and adjusted to provide sufficient tension to lift by far the greater part of the load.
- In the class of graders shown the operator takes a position on the platform 20 and manually turns the wheels 21 whereby through the connection of the worm gears 17, the gears 16, shafts 13, cranks 22 and rods 23 the scraper bar 28 is adjusted. A hexagon head 33^a is attached to the ratchet wheel 33, by means of which a wrench may be used to adjust the ratchet wheel 33.

What is claimed is:

1. In road graders, having a blade or tool

adapted for a working contact with the earth, a rotatable lifting shaft, connections between the lifting shaft and the blade or tool and manually operative means connected with the shaft, a sleeve loosely engaging the lifting shaft, a coil spring engaging the outer surface of the sleeve, means rigidly secured to the shaft for anchoring one end of the spring and to which one end of the spring is anchored and means on the lifting shaft to which the other end of the coil spring is secured, such means being adjustable to change the tension of the spring.

2. In road graders, having a blade or tool adapted for a working contact with the earth, a rotatable lifting shaft, connections between the lifting shaft and the blade or tool and manually operative means connected with the shaft, a sleeve loosely engaging the lifting shaft, a coil spring engaging the outer surface of the sleeve, means in connection with the lifting shaft for anchoring one end of the coil springs to such shaft and means non-rotatable with the lifting shaft for anchoring the other end of the coil spring, such means being adjustable to change the tension of the spring.

In testimony whereof, I affix my signature.

GARFIELD DAVIS.
